TRAY FOR MIXING AUTOMOTIVE BODY MATERIAL AND THE LIKE

Nunzio Valerie, 369 Colvin St.,
Rochester, N.Y. 14611

Filed Mar. 13, 1969, Ser. No. 16,236

Term of patent 14 years

Int. Cl. D15—99

U.S. Cl. D55—1

FIG. 1 is a front elevational view of a tray for mixing automotive body material and the like, showing my new design, the side opposite to that shown being a duplicate of the side shown;

FIG. 2 is an end elevational view of the same, the end opposite to that shown being a duplicate of the end shown;

FIG. 3 is a vertical section taken longitudinally through the center of the tray;

FIG. 4 is a similar section taken transversely through the center of the tray;

FIG. 5 is a top perspective view of the tray; and

FIG. 6 is a perspective view of the under side of the tray.

I claim:

The ornamental design for a tray for mixing automotive body material and the like, substantially as shown and described
